PAPER MAKING MACHINE

Application filed July 15, 1929. Serial No. 378,236.

This invention relates to a paper making machine and more particularly to a forming part of a paper machine, wherein a suction device is provided for forming the web 5 of paper with the aid of suction.

The forming elements of a Fourdrinier paper machine, to which this invention more particularly relates, have persisted for the most part in their original state and in the 10 same relative arrangement without radical change. These forming elements include a breast roll, table rolls, flat suction boxes and a couch roll, and a wire trained around the breast and couch rolls to pass over the table 15 rolls and suction boxes. In such an arrangement, the water is drained from the stock on the wire as it passes over the table rolls largely by gravity and further quantities of water are extracted from the partially 20 formed web as the sheet of stock and wire pass over the suction boxes. In the modern high speed paper machine, the forming part of the machine, that is the table structure, must necessarily be of considerable length in 25 order to provide time for the water to be drained and extracted from the stock to form the web. Aside from the great length, and consequent high cost of equipment, including the forming wire, however, the standard ar- 30 rangement of table rolls and flat suction boxes is a comparatively inefficient means for the removal of water.

In the case of the table rolls on high speed paper machines, the rapid rotation of the 35 relatively small diameter rolls causes a considerable proportion of the water that drains upon the surface of the rolls to be thrown back against the under side of the wire with sufficient force to retard the draining of the 40 water through the wire and also, in some instances, even to disturb the formation of the web. The flat suction boxes present an even more serious problem in that they have a tendency to cause wear upon the wire and 45 decrease its useful life, as well as being themselves worn and scored by the passage of the wire over their surfaces.

It is therefore an object of this invention to provide a novel and improved forming part 50 for paper machines of the Fourdrinier type

wherein the usual table rolls and flat suction boxes are entirely eliminated.

It is a further important object of this invention to provide more efficient means for extracting the water from the stock in the 55 formation of the web so that the forming portion of the paper machine may be considerably shorter and more compact.

It is a further important object of this invention to provide a forming portion of a 60 paper machine wherein the stock is subjected to a continuous suction action from the time it is delivered onto the forming wire until the sheet is formed and sufficient water has been extracted to allow its removal there- 65 from.

It is a further important object of this invention to provide a suction device for cooperation in the formation of a paper web including a traveling perforate cover adapted 70 to travel with and support the forming wire and means for hydraulically balancing the traveling cover against the pneumatic pressure set up by the suction effect.

Other and further important objects of 75 this invention will become apparent from the disclosures in the specification and the accompanying drawings.

This invention (in a preferred form) is illus- 80 trated in the drawings and hereinafter more fully described.

On the drawings:

Figure 1 is a front elevational view of a forming portion of a paper machine embodying the principles of my invention, shown 85 more or less diagrammatically and with parts broken away.

Figure 2 is an elevational view taken substantially on line II—II of Figure 1, with parts removed.

Figure 3 is a top plan view of my suction device.

Figure 4 is an enlarged fragmentary longitudinal sectional view of the breast roll end of the forming portion of the machine.

Figure 5 is an enlarged sectional view taken substantially on line V—V of Figure 3, with parts in elevation and parts removed.

Figure 6 is a fragmentary top plan view of 100 the suction device.

Figure 7 is an enlarged fragmentary sectional view similar to that shown in Figure 5.

Figure 8 is a fragmentary top plan view of the traveling cover for the suction device.

5 Figure 9 is an end elevational view of the cover with a part in section.

Figure 10 is a sectional view taken substantially on line X—X of Figure 9.

As shown on the drawings:

10 The reference numeral 1 indicates the supporting frame of a table structure, including side beams 2 and 3 mounted for lateral removal upon tracks 4 and 5. The specific structure for the removal of the table portion 1 need not be described, since many forms of construction are well known in the art.

15 A forming wire 6 trained around a breast roll 7 and a couch roll 8 cooperates with a suction device, indicated as a whole by the reference numeral 9, in the forming of the web of paper. The usual wire guide roll 10, tension roll 11 and other idling rollers 12 serve their usual function.

20 Stock is introduced onto the forming wire 6 (Figures 1 and 4) from a head box 13 over an apron 14, which is preferably provided with relatively high side boards 15 and hinged as a unit at its upper lateral edges, as at 16, to said head box 13. The apron 14 instead of terminating at the breast roll 7 25 extends completely over the breast roll to carry the stock onto the wire at a point above the suction device 9. Said apron 14 is further provided with a transverse ridge or dam 30 serving to form a pond of stock 17 that is relatively quiescent and free from eddy currents.

35 A slice 18 supported at its ends by the side boards 15, is positioned a considerable distance along the wire to cause an extension 17a of the pond 17 over a portion of the forming wire 6 while it is in cooperation with the suction device 9. The body of stock is thus subject to the suction action of the suction device 9 before it passes out under the slice 18.

40 Said slice 18 may be either of the ordinary low type or may be of the high pressure type. Preferably, means are provided, such as the screws or bolts 80 (Figures 1 and 4), for vertical adjustment of the slice throughout its length and other bolts 81 and blocks 82 extending through slots 83 in the apron side boards 15 for adjustment lengthwise of the wire.

45 A pair of deckle straps 19 mounted upon pulleys 20 and 21 perform the usual function of controlling the width of the sheet on the forming wire 6. The deckle pulleys 20 near the breast roll end of the machine are preferably supported upon the side boards 15 so that they may be elevated together with the apron 14, as indicated in dotted lines in Figure 1, when the table structure is to be laterally removed, as in the changing of a

wire. The other deckle pulleys 21, in such case, may be elevated in any suitable manner and supported in the dotted position shown. In a similar manner, provision is made for elevating the wire rolls 12 into their dotted line position so that the table structure may be rolled out over the supporting tracks 4 and 5.

50 The suction device 9, which embodies the principles of this invention, is of a construction similar to that described in my copending application Serial No. 370,500, filed June 13, 1929. Said suction device 9 comprises a stationary box-like hollow member 22 (Figures 1 and 4), preferably formed in a plurality of transversely divided sections 23, 24, 25, 26, 27 and 28, each forming a separate suction unit, wherein the degree of suction may be individually controlled and varied to suit the operating conditions. The stationary suction member 22 is supported from the side beams 2 and 3 (Figure 2) by means of brackets 29 and 30, respectively.

55 Rolls 31 and 32, suitably journalled in bearing supports 33 and 34, respectively, are mounted from the side beams 2 and 3 at the breast roll and couch roll ends of the suction member 22, respectively. An endless perforate cover 35 for the open top of said suction member 22 is trained around said rolls 31 and 32 and is adapted to be driven by the roll 32 to travel with the forming wire 6. For this purpose, the rear end of the roll 32 (Figure 3) is extended through the rear bearing support 34 to provide an extension 36 on which is mounted a cone pulley 37. A second cone pulley 38 is mounted upon the rearwardly extended shaft 39 of the couch roll 8 and a belt 40 trained over the two cone pulleys 37 and 38 for driving the roll 32 from the couch roll 8. Said couch roll 8 may be driven in any standard manner (not shown).

60 Each of the separate suction units 23 to 28 inclusive, (Figure 2) is connected by means of a suction pipe 41 to a separator 42 having a lower barometric leg 43 extending into a well 44 for receiving the water extracted from the stock and web on the forming wire 6. At the upper end of each of the separators 42 is a valved connection 45 to a header or accumulator 46, from which a pipe 47 leads to a suction fan or blower 48 of any suitable type. The degree of suction in the units 23 to 28 inclusive may thus be controlled individually by the valved connections 45.

65 In the upper portion of the hollow suction member 22 is mounted a plurality of longitudinally extending troughs 49 (Figures 5 to 7 inclusive). Said troughs 49 are adapted to be filled with a liquid, suitably water, through connections 50 from a plurality of transversely extending pipes 51, each extending through packing glands 56 in the side

walls of the member 22 and each connected to a vertical standpipe 52. Each of the standpipes 52 is supplied with water from an inlet valve-controlled pipe 53 and each of said stand pipes 52 is provided with an overflow pipe 54, whereby sufficient head is created to cause the water in the troughs 49 to exert an upward balancing pressure against the traveling cover 35, as will be later explained in greater detail.

The troughs 49 (Figures 6 and 7) comprise relatively shallow boxes, preferably of rectangular cross section, extending the full length of the suction member 22 and supported therefrom on ribs 57. Each of the troughs 49 is spaced from its next adjacent trough by means of integrally formed webs 58, whereby relatively long, narrow openings 59 are provided between adjacent troughs 49 intermediate their ends. The top edges 60 of said troughs 49, as well as the top faces of integrally formed transverse webs 61 extending between the side walls of said troughs are machined to provide plane surfaces for supporting the traveling cover 35. The end walls 62 of said troughs 49 are provided with aligned communicating passages 63, opening upwardly as at 64 between adjacent trough ends. Water is supplied to the passages 63 by means of a pipe 65 under just sufficient pressure to keep the water seeping out through the openings 64, for a purpose that will later appear.

The traveling cover 35 is formed in a plurality of sections 66, each having a base portion 67 (Figures 7 to 10) of slightly greater width than the troughs 49 for resting on the upper machined edges 60 thereof. The belt-like sections 66 are preferably formed of rubber or other resilient material, the base portion 67 being reinforced with fabric plies 68. Transversely extending ribs 69, preferably in the form of an isosceles triangle in cross section, extend upwardly from the base portion 67 and are preferably formed integrally therewith. The ribs 69 may suitably have an outer coating or shell of relatively hard rubber or metal 70 vulcanized or otherwise secured thereto to prevent wear, as it is upon these ribs that the forming wire 6 is supported. The crests of the ribs 69 are provided with minute corrugations 71 upon the tiny crests of which the wire 6 is supported. In this way, there is little or no tendency for the ribs 69 to close any considerable area of the wire 6 to form areas of low suction that would result in faulty formation of the sheet.

Between successive ribs 69, the base portion of the belt sections 66 are cut away as at 72 to provide openings through which the water extracted from the web on the wire may drain. It will be noted that the width of the belt-like sections 66 is such that the openings 72 lie over the longitudinally ex-

tending openings 59 between adjacent troughs 49, so that the water drained from the sheet is free to pass through the openings 72 and 59 into the various sections of the box-like suction member 22. The lateral edges of the belt 66 lie in abutting relation, as at 73, except in the case of the outside belts whose outer edges 74 abut the inside faces of the side rails 55 (Figure 7). The deckle straps 19 overlie the marginal portions of the wire 6 and abut against vertical faces 84 of extension side rails 85 secured to said side rails 55. A groove 86 is formed along each of said inner faces 84, and to each of said grooves 86 is connected a water pipe 87 for supplying water thereto to seal the joints thus formed between the deckle straps, wire and side rails 85.

In operation, stock is allowed to flow from the head box 13 over the apron board 14 and out under the slice 18. The flow of stock under the slice 18 may be under sufficient head to permit the stock to be flowing at substantially the rate of travel of the wire 6 after it passes out from under the slice 18. Inasmuch as the apron board is of imperforate material and extends out over the breast roll 7 to a point beyond the center line of the roll 31, the stock does not flow onto the forming wire 6 until substantially the point is reached at which the wire is first subjected to the suction action of the device 9. Furthermore, since the slice 18 is positioned an appreciable distance along the wire over some intermediate section of the suction device 9, a pond 17a of stock is formed that extends over the area of the wire in front of the slice 18 that is subject to the effect of the suction within the underlying sections, say 23 and 24, of the suction device 9.

Where a low head of stock, say only a few inches, is formed in the ponds 17 and 17a in back of the slice 18, practically all of the forming of the sheet probably takes place in the area covered by the pond 17a with practically no formation occurring after the stock has passed the slice. In this case, the slice would be adjusted so that its lower edge would not be very close to the wire in order not to disturb the top fibers of the deposited layer of fibers on the wire.

As the open wire 6 comes into contact with the suction area over the device 9, the fibers immediately start to deposit on the surface of the wire. The initial layer of fibers formed may be somewhat uneven and spotty due to the small fibers being more or less bunched together, but these fibers are held onto the wire by the action of the suction and are not moved or disturbed by the friction between the moving wire and its deposit of fibers and the pond of stock. The pond is relatively quiescent. As the wire progresses from one end of the area covered by the pond 17a to the other end, the open or thinner spots be-

tween the bunches of fibers first deposited, by offering less resistance to the further flow of water through the wire, tend to cause such further flow, with the result that a uniform 5 and even sheet of fibers is formed on the wire. The flow through the wire is always through the points offering the least resistance, even after a substantial deposit of fibers has occurred.

10 Formation of the sheet accordingly is practically complete before the stock has actually passed under the slice 18 and while there is relatively little forward movement of the stock. Under the action of the suction created by the vacuum pump 48, water is drawn from the pond above the wire and in the course of this draining, the fibers are deposited upon the upper surface of the wire and held there by the suction to build up as just 15 described. The fibers that so settle up before the stock has passed under the slice 18 have no common general direction, owing to the comparatively quiescent state of the pond from which they are deposited, and therefore 20 the tendency is for the sheet to be as strong in one direction as in the other. This, of course, is not true in the case of paper made on the usual type of fourdrinier, where there is a markedly greater strength in the machine 25 direction than in the across-the-machine direction.

In order to eliminate any tendency that the fibers may have to assume vertical or upended positions, a device known to the art 30 may be positioned in the pond 17a to keep the fibers in a horizontal position just previous to coming into contact with the wire. Oscillating or revolving agitators placed close together and to the wire and covering the entire 35 suction area occupied by the pond 17a satisfactorily serve this purpose.

The means including the bolts 81 and blocks 40 82 for connection with the ends of the slice 45 18 permit adjustment of the area covered by the pond 17a for producing various kinds of paper. It is, of course, also possible to vary the speed of the machine to suit operating requirements.

From the time the stock first flows onto the 50 wire until the wire passes beyond the couch roll end of the suction device 9, the stock is subjected to a continuous suction effect. The water extracted from the stock and from the web of sheet during its formation is drawn 55 through the wire into the grooves between the ribs 69 and from these grooves drained through the openings 72 and the openings 59 between adjacent troughs 49 into the various sections 23 to 28 inclusive. From these sections, the water and entrained air are drawn 60 through the pipes 41 into the separators 42, from which the water passes on down through the barometric legs 43 into the well 44 and the air is drawn through the pipes 45, 46 and 65 47 into the vacuum pump 48. The water

from the well 44, which is bound to contain some fibrous material and fillers, may suitably be pumped back into the white water system by means of a pump 74.

Due to the fact that relatively high vacuums are created within the sections 23 to 28 inclusive, there is a considerable pressure above the traveling cover 35 forcing the belt-like sections 66 against the upper surfaces 60 of the troughs 49 and were not this pneumatic pressure balanced in some way, there would be considerable friction developed. According to my invention, however, this pneumatic pressure is effectively balanced hydraulically by supplying water to the troughs 49. The 70 desired head of water thus supplied can be semi-automatically controlled by the height of water within the standpipes 52, which in no event can exceed the height of the overflow pipes 54.

In practice, the pneumatic pressure upon the top surfaces of the belt-like sections 66 due to the partial vacuum created beneath the traveling cover can be, and preferably is automatically balanced by the hydraulic 80 pressure of the water filling the trough 37. This is a particularly important feature of my invention, since it eliminates binding and friction between the belt and supporting surfaces. A variable static head is maintained 85 upon the water within said troughs 49 by the height of the water in the standpipes 52, so that when the pneumatic, or atmospheric pressure is greater than the static head, the level of the water in said standpipes 52 rises 90 automatically until the static, hydraulic pressure balances the atmospheric pressure. Similarly, if the pneumatic pressure for any reason drops below the hydraulic pressure, the water lifts the belt 66 slightly from the tops 95 of the troughs 49 and leaks over into the suction box compartment, thereby reducing the static head.

In effect, therefore, the rubber belts 66 act as regulating valves when provided with a 100 sufficient volume and head of water to automatically balance the pneumatic and hydraulic pressures acting against said belts.

In effect then, the belt-like sections 66 travel upon a film of water that serves both to 115 balance the pneumatic pressure and as a lubricant to prevent wear upon the under surface of said belt. The various joints formed between the belt sections 66 and the contacting surfaces are sealed at the ends of the stationary suction member 22 by the water overflowing from the passages 63 through the openings 64. The joints formed between the inner surfaces 84 of the side rails 85 and the outer ends of the outside belts 66 are sealed 120 against loss of vacuum by the water overflowing from the open channels 86 abutted by the deckle straps 19. The fact that the belt sections 66 are practically running in water continuously is especially conducive 125

to their long life since these conditions are very favorable to rubber, from which the belts are most suitably made.

It will be appreciated that the continuous application of suction to the web on the forming wire makes possible a much more rapid draining of the water from the stock and web than in the case of the usual type of Fourdrinier machine, where the major portion of the draining is effected by gravity alone. Consequently, the length of the forming portion of the machine need be but a fraction of the length of the standard Fourdrinier machine operating under similar circumstances as to speed of travel and type of paper being made. This in itself means a great economy both in space and in cost of equipment, including the forming wire.

The provision for graduating the amount of vacuum at different points of the suction area, as by means of the individual compartments 23 to 28 inclusive and the separate suction connections thereto, is of great value in increasing the operating efficiency of the machine. For instance, as the open wire enters the suction area, if the vacuum were very high it might have a tendency to draw a great many of the smaller fibers through the wire and for this reason it is advantageous to have the vacuum in the first compartment, 23, much lower than in the succeeding compartments, or after the wire has become partly closed from the layer of fibers deposited thereon. The amount of vacuum in these various compartments 23 to 28 inclusive can be varied at will by opening or closing the valve in the connecting air lines 45 leading to the accumulator 46 and vacuum pump 48. It will however be understood that instead of separate suction compartments as shown, a single suction compartment for the entire suction area might be employed.

When it becomes necessary to change the wire to put on a new wire, the apron board 14 and attached side boards 15 are suitably raised about the pivot point 16 and the deckle pulleys 21 are similarly elevated by the usual deckle elevating mechanism. The wire rolls 12 are likewise raised and suitably suspended beneath the side beams 2 and 3. The table structure 1 is then rolled out laterally on the front side of the machine over the transfer tracks 4 and 5 and suitably positioned outside track members (not shown). A new wire, indicated in dotted lines in Figure 1, is then suspended in looped position by means of a plurality of spindles 75. The couch roll 8, which may or may not be a suction couch, may suitably be of the cantilever type to permit the insertion of the loop of the wire 6 over said roll from one end thereof. With the wire so suspended, the table structure 1 is again rolled into place, the spindles 75 removed and the wire rolls 12 and deckle pulleys and apron again placed in their normal position.

I am aware that many changes may be made and numerous details of construction may be varied through a wide range without departing from the principles of this invention, and I, therefore, do not purpose limiting the patent granted hereon otherwise than necessitated by the prior art.

I claim as my invention:

1. In a Fourdrinier paper machine, including a breast roll, couch roll and traveling forming wire, a suction device extending substantially the full distance between the breast roll and couch roll for cooperation with said wire to apply suction therethrough to form a continuous sheet thereon.

2. In a paper machine, including a breast roll, couch roll and forming wire, a suction device comprising a stationary suction member having a traveling perforate cover supporting and cooperating with the wire during the greater portion of its effective length.

3. In a Fourdrinier paper machine, including a breast roll, couch roll and forming wire, a suction device cooperatively associated with the forming wire during travel thereof and taking the place of the usual table rolls and stationary suction boxes.

4. In a paper machine of the Fourdrinier type including a forming wire, a suction device, a traveling perforate cover therefor cooperatively associated with said wire and means for delivering stock onto said wire while the stock receiving portion of said wire and cover are traveling together in cooperative relation.

5. In a paper machine of the Fourdrinier type including a forming wire, a stationary suction member positioned beneath the upper run of the wire and substantially coextensive therewith and a hydraulically balanced perforate cover for said member through which suction is applied to said wire.

6. In a paper machine of the Fourdrinier type including a forming wire, a stationary suction member positioned beneath the upper run of the wire and substantially coextensive therewith, a hydraulically balanced perforate cover for said member through which suction is applied to said wire and means for moving said cover in supporting relation to said wire at the same speed as said wire.

7. In a paper machine of the Fourdrinier type including a stock head box, apron, slice and forming wire, the slice being positioned a substantial distance down the wire, a stationary suction device positioned beneath the upper run of the wire and a perforate cover for said device cooperatively associated with said wire and traveling therewith, whereby suction is applied to said wire before the stock has passed under the slice.

8. In a paper machine of the Fourdrinier type including a stock head box, apron, slice and forming wire, the slice being positioned a substantial distance down the wire, a sta-

tionary suction device positioned beneath the upper run of the wire and a perforate hydraulically balanced cover for said device cooperatively associated with said wire and 5 traveling therewith, whereby suction is applied to said wire before the stock has passed under the slice.

9. In a paper machine of the Fourdrinier type including a forming wire and means for 10 delivering stock thereunto, a stationary suction device substantially coextensive with the forming part of the wire and a traveling perforated cover therefor cooperatively associated with said wire, whereby suction may 15 be continuously applied to said wire through said traveling cover from the point of delivery of the stock thereonto until the web has been formed.

10. In a paper machine of the Fourdrinier type including a forming wire, means replacing the usual tube rolls and flat suction boxes comprising a stationary suction member and a traveling perforate cover therefor cooperatively associated with the forming wire 20 25 for applying a continuous suction thereto throughout substantially the entire length of the forming portion thereof.

11. In a paper machine of the Fourdrinier type including a forming wire, means replacing the usual tube rolls and flat suction boxes comprising a stationary suction member and a hydraulically balanced traveling perforate cover therefor cooperatively associated with the forming wire for applying a continuous 30 35 suction thereto throughout substantially the entire length of the forming portion thereof.

12. In a paper machine of the Fourdrinier type including a forming wire, means replacing the usual tube rolls and flat suction boxes comprising a stationary suction member, a traveling perforate cover therefor cooperatively associated with the forming wire for applying a continuous suction thereto throughout substantially the entire length of 40 45 the forming portion thereof and means for delivering stock to said wire at a point where the wire is subjected to suction.

13. In a paper machine of the Fourdrinier type including a head box, breast roll, couch 50 roll and forming wire, a suction device for the continuous application of suction to the forming wire and an apron extending from said head box over the breast roll to deliver stock onto the wire at a point subject to the 55 suction created by said device.

14. In a paper machine of the Fourdrinier type including a head box, breast roll, couch roll and forming wire, a suction device for the continuous application of suction to the forming wire, an apron extending from said head box over the breast roll to deliver stock onto the wire and a slice beyond the end of the apron for forming a pond of stock subject to the suction created by said device.

15. The combination with a continuously

traveling forming wire of a paper machine, of means for forming a pond of stock over the receiving end of said wire and means for continuously applying suction to that portion of the wire covered by said pond of 70 stock.

16. The combination with a continuously traveling forming wire of a paper machine, of means including an imperforate apron, apron side boards and a slice for forming a 75 pond of stock over the receiving end of said wire and means for continuously applying suction to that portion of the wire covered by said pond of stock.

17. The combination with the forming 80 wire of a paper machine of the Fourdrinier type, of means for forming on said wire a pond of stock of substantial depth extending over a substantial portion of the length of said wire and means for applying a continuous 85 suction through the portion of the wire so covered and until sheet is formed.

18. The combination with the forming wire of a paper machine of the Fourdrinier type, of means for forming on said wire a 90 pond of stock of substantial depth extending over a substantial portion of the length of 95 said wire and means positioned beneath the upper run of the wire and coextensive with the major portion of the length thereof for applying a continuous suction through the portion of the wire so covered.

19. The combination with the forming wire of a paper machine of the Fourdrinier type, of a stationary suction member positioned beneath the upper run of the wire and coextensive with a major portion thereof and a perforate cover for said member for supporting said wire without relative movement 100 between the contacting surfaces. 105

20. The combination with the forming wire of a paper machine of the Fourdrinier type, of a stationary suction member positioned beneath the upper run of the wire and coextensive with a major portion thereof, a 110 perforate cover for said member for supporting said wire without relative movement between the contacting surfaces, means for forming a pond of flowing stock under appreciable head over a portion of the wire supported by said cover and means for creating a partial vacuum within said suction member for the application of suction through 115 said cover.

21. A paper machine of the removable 120 Fourdrinier type comprising a forming part including a wire and a suction device cooperatively associated with the upper run thereof for a greater portion of its length for continuously applying suction through 125 the traveling wire and means for laterally removing said table structure.

22. In a paper machine of the removable Fourdrinier type, a forming part comprising a breast roll, a couch roll, a suction device be- 130

5 tween said rolls and having a traveling perforate cover and a wire trained around said breast and couch rolls and supported on said cover and means for moving said suction device out from between said breast roll and couch roll.

10 23. In a paper machine, a forming part including a breast roll, couch roll and a forming wire passing therearound, a suction device having a traveling perforate cover through which suction is applied to the wire throughout a major portion of the upper run thereof and means for driving said cover from the couch roll at the same rate of speed 15 as said wire.

15 24. In a paper machine, a forming part including a breast roll, couch roll, a forming wire passing therearound, a suction device substantially coextensive with the upper run 20 of said wire, a cover for said device having openings therethrough for the application of suction to said upper run of wire, means for driving said cover, and means for sealing the joints between said cover and said device to 25 prevent loss of suction.

30 25. In a paper machine, a forming part including a breast roll, couch roll, a forming wire passing therearound, a suction device substantially coextensive with the upper run 35 of said wire, a cover for said device having openings therethrough for the application of suction to said upper run of wire, means for driving said cover, and means including liquid seals and deckle straps for sealing the joints between said cover and said device to 40 prevent loss of suction.

45 26. In a paper machine, a forming part including a breast roll, couch roll, a forming wire passing therearound, a suction device substantially coextensive with the upper run 50 of said wire, a cover for said device having openings therethrough for the application of suction to said upper run of wire, means for driving said cover, means for hydraulically balancing the pneumatic pressure against 55 said cover, and means for sealing the joints between said cover and said device to prevent loss of suction.

60 27. The method of forming a sheet of paper or the like, which comprises subjecting a pond of stock supported upon a traveling foraminous surface to a continuous suction through said surface, allowing the stock to flow from said pond under regulated head 65 and continuing the application of suction through said surface until the web is formed.

70 28. The method of forming a continuous web of paper or the like, which comprises depositing fibers from a flowing dilute water suspension of fibers under the action of relatively high suction and continuing the application of suction without interruption until the web is formed.

75 29. The method of forming a continuous web of paper or the like, which comprises

initially depositing fibers under the action of suction from a pond of stock in a state of comparative quiescence onto a traveling foraminous surface, allowing the stock while still under the action of suction to flow with 70 said foraminous surface at substantially the same speed as the traveling surface and continuously applying suction through the traveling foraminous surface until the web is formed. 75

80 30. The method of forming a continuous web of paper or the like, which comprises depositing fibers from a dilute water suspension of fibers in the form of a flowing stream by the application of suction thereto and 85 continuously applying suction to said fiber suspension from the time of first fiber deposition until the web is formed.

85 31. The method of forming a continuous web of paper or the like, which comprises depositing fibers from a flowing dilute water suspension of fibers under the action of successively graduated degrees of suction and continuing the application of suction without interruption until the web is formed. 90

95 32. In a Fourdrinier paper machine, including a breast roll, couch roll and endless forming wire continuously traveling around said breast and couch rolls, a suction device extending from said breast roll a substantial distance toward said couch roll and a driven perforate cover cooperating with said suction device and forming wire to support the latter and permit the continuous application of suction through said wire to the stock 100 flowing thereon.

105 33. In a Fourdrinier paper machine, including a breast roll, couch roll and endless forming wire continuously traveling around said breast and couch rolls, a suction device extending from said breast roll a substantial distance toward said couch roll, a driven perforate cover cooperate with said suction device and forming wire to support the latter and permit the continuous application of suction through said wire to the stock flowing 110 thereon and means including an imperforate apron extending over said breast roll to deliver stock onto said forming wire at a point where said wire is subjected to the action of said suction device. 115

In testimony whereof I have hereunto subscribed my name at Beloit, Rock County, Wisconsin.

EARL E. BERRY. 120
